UNITED STATES PATENT OFFICE.

BENTON C. ROWELL, OF CHICAGO, ILLINOIS, ASSIGNOR TO ANCHOR BRAKE SHOE AND MANUFACTURING COMPANY, OF CHICAGO, ILLINOIS, A CORPORATION OF ILLINOIS.

BRAKE-SHOE.

1,187,466.

Specification of Letters Patent. Patented June 13, 1916.

Application filed January 2, 1915. Serial No. 50.

To all whom it may concern:

Be it known that I, BENTON C. ROWELL, a citizen of the United States, and a resident of Chicago, in the county of Cook and State 5 of Illinois, have invented certain new and useful Improvements in Brake-Shoes, of which the following is a specification.

My present invention relates to wearing brakes or shoes such as are commonly used 10 on railway rolling stock and more particularly to brake shoes for this purpose which are reinforced and contain wear resistance inserts of harder material than the body of the shoe.

15 The principal objects of my present invention are to provide improved means for connecting the body of the shoe, the wearing inserts and the reinforcement; to provide improved means for preventing sections of 20 the body of the shoe from falling should fracture occur; to provide means whereby the reinforcement itself is used to connect the shoe to its support; to provide improved means for localizing the pressure of the 25 brake shoe to those parts of the wheels which are least worn by the rails; and generally to improve, cheapen and simplify the construction of brake shoes for railway and other vehicles together with such further objects as will hereinafter appear.

In attaining the foregoing objects and certain additional advantages to be below disclosed, I have provided the constructions illustrated in the accompanying drawings, 30 wherein:—

Figure 1 shows in elevation a shoe constructed in accordance with the present invention; Fig. 2 is a plan view of the shoe illustrated in Fig. 1; Fig. 3 is a vertical transverse section on the plane 3—3 of Fig. 40 1; Fig. 4 is an elevation of a modified form of shoe; Fig. 5 is a plan view of the shoe shown in Fig. 4; Fig. 6 is a vertical transverse section on the plane 6—6 of Fig. 4; Fig. 7 is a plan view of the reinforcement used for a modified form of shoe; Fig. 8 is a vertical transverse section through shoe 45 embodying the reinforcement shown in Fig. 7; and Fig. 9 is a perspective view of the 50 supporting strap used in the form of shoe illustrated in Fig. 8.

Reference will now be made to Figs. 1 to 3 which illustrate the first of these various forms. The brake shoe consists of a body 55 portion 10 provided with two series of wear-

ing inserts 11 and 12. The first set of inserts is arranged over the flange of the wheel as will be clearly seen from Fig. 3. The second set of wearing inserts is arranged to contact with the outer part of the flat portion of the wheel. It will be observed that the wearing inserts 11 and 12 come into frictional engagement with those parts of the wheel which are little worn by the rails. Not only are these hard inserts of harder or 60 different metal localized to those parts of the wheels where there is little normal wear but in addition a groove 13 is formed along the under surface of the body of the shoe 65 opposite the point at which the wear is greatest. This groove allows the parts of 70 the brake shoe on either side to wear away considerably before the brake shoe has any abrading action on the portion of the wheel 75 which normally comes into contact with the rails.

The brake shoe is reinforced by means of inverted channel members 14 and 15, preferably arranged as shown along the upper surface of the brake shoe. Although the reinforcement is in contact with the body of the shoe along its vertical faces only it is 80 securely connected to the body portion by means of the wearing inserts. For this purpose apertures 16 and 17 respectively are 85 arranged in the reinforcing members through which upwardly expanding projections 18 and 19 from the inserts 11 and 12 extend. To enable these projections to grip the reinforcement the edges of these 90 apertures are depressed below the normal surface of the channeled iron in such a way as to form what are practically countersunk apertures adapted to engage the conically 95 formed ends 18 and 19 of the inserts. While 100 the projecting ends 18 and 19 of these inserts are arranged upwardly expanding in order to engage the reinforcement the body part of the inserts is arranged so that it expands downwardly. The object of this is to draw the body of the shoe and the reinforcement together and also to prevent sections of the brake shoe from falling should fracture occur. It will be evident that any fragment of the brake shoe which extends more 105 than half around any one of the inserts will in general be held thereby and prevented from falling. Both sets of inserts are formed with flat surfaces perpendicular to the vertical side faces of the shoe and in- 110

clined downwardly and outwardly with respect to each other.

While it is desirable to provide means for preventing sections of the brake shoe from moving downwardly with respect to the inserts it is also desirable to prevent movement of the body of the brake shoe upwardly relatively to the inserts, particularly in view of the fact that the support for the brake shoe is attached to these inserts rather than to the body of the shoe itself. Accordingly, in the case of the inserts 11 the lower ends are shaped so as to form an inwardly inclined surface 20 against which the portion 15 21 of the body of the brake shoe bears in order to prevent such upward movement relatively to the inserts 11. The shoulders 33 and 34 on the inserts 12 and the part 22 of the body of the shoe perform a similar 20 function in connection with the other set of inserts 12.

The reinforcement 14 is arranged along the upper surface of the shoe and is arranged to extend through the upraised parts 25 23 and 24 at the two ends of the shoe (see Fig. 1). In the case of the reinforcement 15, however, each end is turned upwardly so as to provide the necessary resistance to longitudinal movement of the shoe on its 30 support. At one end the center web is cut away and the flanges of the channel iron turned up so as to provide abutments 25. At the other end the flanges of the channeled reinforcement are cut off before the 35 upturned end is reached in order to leave a flat tang 26 which can be bent over the end of the support when the shoe has been placed in position thereon. The support for the shoe fits into the recessed part between the upraised ends 23 and 24 and is held there by means of the tang 26.

Referring now to the modified form of brake shoe illustrated in Figs. 4 to 6 it will be seen that in its main outlines the construction is similar to that already described in connection with Figs. 1 to 3. The principal features of distinction consist, first, in the arrangement of the reinforcement and secondly in the omission of the 45 groove 13 in the body portion of the brake shoe and the provision of a set of inserts which extend practically up to the flange of the wheel thus covering the whole flat surface of the wheel.

With regard to the reinforcement it will be seen that the reinforcement 14 over the flange of the wheel is the same as that illustrated in Fig. 3 in its general arrangement and also in cross section. The other reinforcement 50 27 is distinguished from the corresponding reinforcement 15 in that its ends 28 and 29 are not upwardly turned nor do they extend into the upraised ends 23 and 24 of the shoe. Further, instead of the reinforcement itself being employed as the con-

necting means between the brake shoe and its support a separate strap 30 is provided adapted to straddle the main channeled reinforcement 27 at its center. Suitable lips 31 at the lower ends of this strap 30 are provided for engaging with the under surface of the flanges of the channeled reinforcement. With regard to the wearing inserts 32 these are distinguished from the corresponding inserts 12 in the other form of construction by the fact that they are provided with vertical ends on either side and are arranged so as to extend over substantially the whole width of the flat portion of the wheel.

In Figs. 7 to 9 a form of construction is illustrated which is designed particularly to allow the brake shoe to wear away to a greater extent than is possible in the forms illustrated in the preceding figures. An 5 examination of Fig. 6 will show that as soon as the turned over ends 31 of the supporting strap 30 have been worn away no positive means exist preventing the strap 30 from pulling out of the shoe. Similarly 90 when the shoe has worn away to the bottom of the conical parts 17 of the reinforcement 15 there is nothing to hold together the parts 19 of the inserts 12 and the other parts of such inserts.

In order to enable the supporting lug, reinforcement, and wearing inserts to be securely locked together until the shoe has been worn so thin that it has not the requisite mechanical strength, the construction 100 illustrated in Figs. 7 to 9 has been provided. In the form shown in Figs. 7 to 9, the supporting strap 48 is formed with offset ends 40 adapted to be passed through apertures 41 in the reinforcement 42. 105 These slots 41 are made slightly wider than the thickness of the supporting strap in order to enable the offset ends to be passed therethrough as shown in Fig. 8. To prevent the disengagement of the strap and the reinforcement I prefer not to rely on the metal of the insert which is cast around these offset ends, so I bend parts of the reinforcement itself into secure engagement with these ends. For that purpose I form a slit or aperture 43 at the center of the reinforcement and bend the edges 44 of such slot or aperture around so as to engage the offset ends 40 as shown in Fig. 8. It will be observed that any pressure exerted upwardly on the strap will tend to draw the edges 44 upward and thereby produce a stronger lock between the reinforcement and the strap than was originally the case. Attention should also be called to the fact that as a slot is employed instead of a circular aperture having conically depressed sides the metal between the edges 44 will be connected to the remainder of the inserts at the ends of the slot even if by wear the insert 110 120 125 130

has been worn down to the edges 44 adjacent the center of the slot. While the edges 44 are downwardly and outwardly inclined at their center toward their ends they are 5 downwardly and inwardly inclined so as to grip with the insert until the latter has been worn almost completely away.

Although in the forms of construction shown in Figs. 7 to 9 the means used for 10 connecting the supporting strap and the reinforcement are arranged so as to unite the reinforcement to the wearing inserts, it is understood that where several wearing inserts are employed those wearing inserts 15 which are not adjacent the supporting strap may be connected to the reinforcement by means of slits similar to slit 43 in Fig. 7 to prevent loosening of the inserts by wear.

Having thus described my invention and 20 illustrated its use what I claim as new and I desire to secure by Letters Patent.

1. A brake shoe comprising in combination a body portion, reinforcement adjacent the upper part of said body portion, a series 25 of wearing inserts comprising parts upwardly expanding in all directions for engagement with said reinforcement and downwardly expanding parts for engagement with the body portion.

30 2. A brake shoe comprising in combination a body portion, reinforcing members of inverted channeled cross section having a series of apertures the entire edges of which are depressed below the normal surface of 35 the reinforcement and a series of wearing inserts comprising an upwardly expanding part for engagement with said reinforcement by means of said apertures and a downwardly expanding part for engagement 40 with said body portion.

3. A brake shoe comprising in combination a body portion, reinforcement adjacent the upper part of said body portion having a series of apertures therein with 45 curved upwardly and outwardly extending walls, a series of wearing inserts comprising an upwardly expanding part for engagement with said reinforcement by means of said apertures and downwardly expanding 50 parts for engagement with said body portion.

4. A brake shoe comprising, in combination, a body portion, reinforcement adjacent the upper part of said body portion 55 having swaged apertures therein, a series of wearing inserts comprising upwardly expanding parts for engagement with the swaged apertures of said reinforcement, and downwardly expanding parts for engagement 60 with the body portion.

5. A brake shoe comprising, in combination, a body portion, reinforcing members of inverted channeled cross section having a series of substantially circular apertures the 65 edges of which are depressed below the nor-

mal surface of the reinforcement and a series of wearing inserts comprising an upwardly expanding part for engagement with said reinforcement by means of said apertures, and a downwardly expanding part 70 for engagement with said body portion.

6. A brake shoe comprising in combination a body portion, channeled reinforcement adjacent the upper part of said body portion, upwardly turned ends on said reinforcement adapted to prevent longitudinal movement of the shoe relatively to its support, the flanges of the reinforcement being cut away adjacent one end thereof whereby the intervening web can be bent over the 75 support for the shoe.

7. A brake shoe comprising in combination a body portion, channeled reinforcement adjacent the upper part of said body portion, having the central web cut away 80 adjacent one end thereof and the flanges cut away adjacent the other end thereof, the flanges and central web so left being turned upwardly whereby longitudinal movement of the shoe relatively to its support is prevented.

8. A brake shoe comprising, in combination, a body portion, reinforcement adjacent the upper part of said body portion having a series of substantially circular apertures therein with upwardly and outwardly extending walls, a series of wearing inserts each having an upwardly expanding part for engagement with said reinforcement by means of said apertures, and downwardly 90 expanding parts for engagement with said body portion.

9. A brake shoe comprising in combination a body portion having a groove opposite the part of the wheel where the normal 105 wear is greatest, a wearing insert of substantially the same width as the tread portion of the wheel adapted to contact with the outer part of said tread portion of the wheel having a cutaway part adjacent said 110 groove.

10. A brake shoe comprising, in combination, a body portion, inverted channeled reinforcement therefor, apertures in said reinforcement having depressed edges and inserts cast between the depressed edges of 115 said apertures and the flanges of the reinforcement whereby the insert is firmly locked in place.

11. A brake shoe comprising in combination a body portion, an external reinforcing member therefor having apertures therein with curved edges, the portions around said apertures being depressed and inserts of different material cast *in situ* so as to extend 120 through said apertures whereby the insert is firmly locked in place.

12. A brake shoe comprising in combination a body portion, inverted channeled reinforcement therefor, apertures in said rein- 130

forcement having depressed curved edges and inserts cast between the depressed edges of said apertures and the flanges of the reinforcement whereby the insert is firmly 5 locked in place.

13. A brake shoe comprising, in combination, a body portion, an external reinforcing member therefor having a substantially circular aperture therein, the portions 10 around said aperture being depressed and an insert of different material cast *in situ* so as to extend through said aperture whereby the insert is firmly locked in place.

14. A brake shoe comprising in combination a body portion, channeled reinforcement adjacent the upper part of said body portion, an upwardly turned end on said reinforcement, the flanges of the reinforcement

being cut away adjacent said upturned end whereby the intervening web can be bent 20 over the support for the shoe.

15. A brake shoe comprising, in combination, a body portion, inverted channeled reinforcement therefor, substantially circular apertures in said reinforcement having depressed edges and inserts cast between the depressed edges of said apertures and the flanges of the reinforcement whereby the insert is firmly locked in place. 25

In testimony whereof I have hereunto signed my name in the presence of the two subscribed witnesses,

BENTON C. ROWELL.
